HELICAL MULTIPLE PUMP

René Joseph Louis Moineau, Paris, France; Adele Moineau, administratrix of said René Joseph Louis Moineau, deceased, assignor to Robbins & Myers, Inc., Springfield, Ohio, a corporation of Ohio

Application June 18, 1946, Serial No. 677,610

5 Claims. (Cl. 103—4)

1

This invention relates to a helical multiple pump and more particularly to a multiple cylinder pump the individual cylinders of which embody the principles disclosed and claimed in my U. S. Patent No. 1,892,217, dated December 27, 1932.

In that patent I have described the theory of operation and general principles of pumps having internal and external helical gear elements, and in which the external element has one more thread than the internal element; for example, the external element may have a double thread whereas the internal element has a single thread, or the external element may have a triple thread, while the internal element has a double thread.

Pumps operating upon the principles discussed in my above mentioned patent have numerous advantages which make their use desirable in cases where high capacity is desired.

It is therefore, an object of my invention to provide for the utilization of the principle disclosed in my above mentioned patent in multi-cylinder pumps whereby the output of the pump can be increased many times.

It is another object of my invention to provide a pump utilizing the principles mentioned above which will eliminate the need for thrust bearings because the operation of the pump is axially balanced. It is a further object of my invention to provide a pump along the lines discussed above which needs, however, only a single packing gland, and which will therefore be cheaper to maintain than conventional multi-cylinder pumps.

A still further object of my invention comprises the elimination of connecting rods such as are found in conventional pumps. In general, my objects include the provision of a multi-cylinder pump which will be completely balanced, which will have a high capacity, which will be inexpensive to maintain and which will have a minimum of moving parts.

These and other objects of my invention which will be pointed out in more detail hereinafter, or which will be apparent to one reading these specifications, I accomplish by that certain construction and arrangement of parts of which I shall now describe an exemplary embodiment.

Reference may be made to the drawings forming a part hereof and in which

Figure 1 is a diagram illustrating the principle involved in the present invention.

Figure 2 is a diagrammatic representation in cross section of a simple embodiment of my invention.

Figure 3 is a cross-sectional view taken on the line 3—3 of Figure 4, showing a four-cylinder pump according to my invention.

Figure 4 is a cross-sectional view taken on the line 4—4 of Figures 3 and 6.

Figure 5 is a cross-sectional view taken on the line 5—5 of Figure 6, and

Figure 6 is a cross-sectional view taken on the line 6—6 of Figure 4.

10 Briefly in the practice of my invention, I assemble a pair of basic pump elements such as are illustrated in my above mentioned patent, and having one and two threads or teeth respectively, in axial relation so that the rotors of the 15 two basic pumps are common; then with the external elements of the two pumps fixed, the common rotor may be gear driven, as will be described hereinafter, and if the common rotor has two portions of opposite hand so that the pumping 20 thrust is exerted in opposite directions, end thrust is eliminated.

From a study of my above mentioned patent it can be ascertained that assuming the external element to be fixed, the internal element 25 will roll on the inside of the external element. The path of the axis of the internal element will be a circle; but the path of any point on the generating circle of the internal element, where the external element has a double thread and the 30 internal element a single thread, will be in a straight line.

In Figure 1 I have shown the situation diagrammatically. The generating circles of the rotor and stator are indicated respectively C_1 and C_2 , 35 the circle C_1 having its center at O_1 , and the circle C_2 having its center at O_2 . If now a gear P_1 is so attached to the rotor that its center as seen on the diagram on Figure 1 is located at O_2 with respect to the rotor generating circle C_1 , then 40 during revolution of the rotor the center of the gear P_1 will traverse the straight line $O_3—O_4$. In other words, as the rotor and its gear P_1 rotate the center of the gear P_1 oscillates back and forth in a straight line. The direction of the line of 45 oscillation is dictated by the phase relationship between the stator and rotor and it follows that in order to produce a condition where the line $O_3—O_4$ is at a right angles to the gear interaxial line $O_2—O_5$, careful orientation of the stator and 50 rotor are necessary. In this situation the axis of the gear P_1 is displaced a distance $O_1—O_2$ from the axis of the rotor.

The gear P_1 may be driven by a gear P_2 whose center O_5 is on the perpendicular bisector of the line O_3, O_4 . From a consideration of Figure 1, it

will be seen that the interaxial distance between the gears P_1 and P_2 will vary from a maximum O_3, O_5 to a minimum O_2, O_5 .

The maximum of the possible differences between O_3, O_5 and O_2, O_5 is :

$$O_3, O_5 (1 - \cos \alpha)$$

α being defined by:

$$\tan \alpha = \frac{2 \times \text{eccentricity of pump } (O_1, O_2)}{O_2, O_5}$$

It is known that for small values of the angle α , $(1 - \cos \alpha)$ is less than

$$\frac{\alpha^2}{2}$$

If, for example, the eccentricity of the pump is 2 mm., and the interaxial distance between the gears is 40 mm., and since the distance O_2, O_3 is twice the eccentricity of the rotor O_1, O_2 , it will be seen that the tangent of the angle alpha is .1, and the angle alpha is a little less than 6 degrees, the cosine of 6 degrees is 0.995, from which it appears that the distance O_3, O_5 will only differ from the distance O_2, O_5 by one half of 1 percent.

As has been described above, the path of movement of any point on the generating circle of the rotor will be a straight line, but depending upon the orientation of the stator this straight line may be horizontal or vertical, or at any angle in between. The situation shown in Figure 1 is that in which the stator is so oriented that this path of oscillation is perpendicular to a line connecting the axes of the gears. When the device is in use, the gear P_1 will move to right and left of Figure 1, between the points O_3 and O_4 , but since the variation from the proper pitch distance is only one-half of 1 percent, the drive will function properly.

In Figure 2 I have shown more or less diagrammatically how this principle may be utilized. I have indicated a pair of stator elements 10 and a pair of rotors 11, with the rotors 11 being mounted on a single shaft 12. The rotors 11 will preferably be of opposite hand so that the pumping effect will be in opposite directions. It will be observed that the stators 10 have double threads, while the rotors 11 have single threads. A gear 13 is mounted on the shaft 12, which it will be noted, is eccentric to the rotors 11. This eccentricity must be such that by virtue of its relation to the center of mass of the rotor, the center of the gear lies on the generating circle of the rotor, whereby the center of the gear oscillates in a straight line while the center of the rotor moves in a circular path. The gear 13 may be driven by a gear 14, through power applied to the shaft 15. The entire arrangement is enclosed within a housing 16, having an inlet port 17, communicating with the inner ends of the two pumps, and an exhaust port 18, communicating with the outer ends of the two pumps. In the device of Figure 2, the fluid to be pumped enters through the port 17 and follows the direction of the arrows through the two pumps, and emerges through the port 18. It will be observed that end thrust is completely neutralized so that there is no need for any thrust bearing, and that the pump requires only a single packing gland at 19. Since there is no restriction in the mechanism which would prevent full reversibility, it is also possible to reverse the rotation of the mechanism, in which case the ports 18 and 17 of Fig. 2 will be in a reversed relationship to that described above.

In Figures 3, 4, 5 and 6, I have illustrated an

eight cylinder pump embodying the principles discussed hereinabove. As will be clear from the drawings, it comprises four pairs of pumping elements, each pair being axially aligned and the four pairs being uniformly distributed about the central axis of the pump. The various stators are indicated at 20, and they are fixed in the housing, which is indicated generally at 21. The rotors for each pair are indicated at 22, and may be continuous or integral, or they must be separate and joined together in the center within their respective driving pinions 23. This may be accomplished by taper pins 24, or in any suitable manner. The respective stators are so oriented (see Figure 5), that the paths of oscillation of the centers of the driving pinions 23 will be perpendicular to a line connecting the axis of the respective cylinders with the central axis of the pump. The four rotors for the eight stators are driven by a single central gear 25 keyed to the drive shaft 26.

The casing of the pump may be in three parts with a central portion 21 carrying the inlet and exhaust ports 28 and 29 respectively, to which may be bolted the end casings which have already been designated as 21. For convenience in manufacture the casing elements 21 may be identical, in which event the element which is not at the driving end of the pump may have the cored opening 30 plugged as by a plug 31. The cored opening in the drive end housing 21 may be further machined to provide a seat for the bushing 32, and have a packing gland arrangement 33. This will not be described in detail since it forms no part of my invention. However, it is significant to note that in the entire pump the only packing gland required is at 33. The end of the shaft 26 may be splined as at 34 for connection to a driving motor.

The inlet port 28 leads to the central portion of the pump from where the fluid is pumped outwardly through all eight cylinders, into the annular manifolds at each end of the pump indicated at 35. The manifolds 35 communicate with the ducts 36, and lead to the outlet port 29.

It will be clear from the foregoing that I have provided a multi-cylinder pump in which end thrust is entirely eliminated, and which is dynamically balanced so as to run smoothly and quietly. It will also be clear that I have eliminated all but a single packing gland.

While I have shown gear drives in the drawings, it will be understood that, provided the principles herein disclosed are observed, the drive may be accomplished by means of chain and sprocket drives or belt and pulley drives if desired. Numerous modifications may, of course, be made without departing from the spirit of my invention, and I do not therefore intend to limit myself as set forth in the claims which follow.

The term "Moineau element" as used in the claims, means an assembly of an external helical gear member and an internal helical gear member in which the external member has a double thread and the internal member has a single thread, whereby if the external element is held against movement, any point on the generating circle of the internal element will oscillate in a line transverse to the axis thereof.

Having now fully described my invention, what I claim as new and desire to secure by Letters Patent is:

1. A mechanism comprising a pair of hypocycloidal gear elements of the type in which the axis of the internal element moves in a circular

path, the external element being fixed, an eccentric shaft for said internal element, a drive shaft for said pair of elements, and a driving connection between said drive shaft and said eccentric shaft, said elements being so oriented, and said eccentric shaft having such an eccentricity that the path of oscillation of said eccentric shaft is perpendicular to a line connecting the axis of said eccentric shaft and said drive shaft.

2. A pump having an inlet and an outlet, and comprising inner and outer helical screw elements in engagement, and cross-sectional shapes of hypocycloidal generation, the inner screw element having a single thread and the outer element having a double thread, said outer element being fixed, a shaft for said inner element, power transmission means on said shaft, a drive shaft for said pump and power transmission means on said drive shaft in operative relationship with said first mentioned power transmission means, said inner and outer elements being so oriented and the shaft for said inner element having such an eccentricity with respect to said inner element that the path of oscillation of said inner element shaft is perpendicular to a line connecting the axes of said shafts.

3. A multiple pump having an inlet and an outlet, and comprising two fixed outer helical screw elements and two inner helical screw elements in engagement therewith respectively, each of said outer elements having two threads, and each of said inner elements having one thread, the threads of one engaging set of inner and outer elements being of opposite hand from the threads of the other set of inner and outer elements, said inner elements being fixed together to constitute a common rotor, a pinion on said rotor and a driving gear for said pinion,

the sets of said inner and outer elements being so oriented and said pinion having such eccentricity with respect to said rotor that the path of oscillation of said pinion is perpendicular to a line connecting the axis of said pinion to the axis of said gear.

4. A pump according to claim 3 in which there are at least three pairs of interengaging sets of helical elements, the elements of each pair being of opposite hand and each pair of said elements having a common rotor and fixed stators, said pairs being symmetrically distributed about the central axis of said pump, a pinion on each of said rotors and a single driving gear for all of 15 said pinions on said central axis, said pairs of elements being so oriented and said pinions having such an eccentricity with respect to their respective rotors that the path of oscillation of each of said pinions is perpendicular to a line connecting the axis of the respective pinion with the central axis of the pump.

5. A pump according to claim 4 comprising four pairs of interengaging sets of such elements.

RENÉ JOSEPH LOUIS MOINEAU.
